DEMOUNTABLE ROCK BIT

John T. Phipps, Huntington Park, Calif., assignor to W. K. P. Oil Tool Co., a corporation of California

Application December 19, 1938, Serial No. 246,643

21 Claims. (Cl. 255—71)

This invention relates to roller bits for use in rotary drilling, and has as a broad object to provide a roller bit construction which can be readily disassembled and reassembled to permit repair or replacement of the wearing parts.

Another object is to provide a roller bit that is exceptionally strong and rigid and has large bearing surfaces for rotatably supporting the cutting rollers.

10 Another object is to provide a roller bit having a cross cutter roller assembly adapted to be preassembled as a unit, and inserted and removed from the bit as a unit.

Other minor objects and features of the invention, and the manner in which they, together with the foregoing objects, are achieved, will now be explained by describing in detail, with reference to the drawing, a specific embodiment of the invention.

20 This is in part a continuation of my application Serial No. 165,910, filed September 27, 1937 on Roller bits, now Patent Number 2,145,573, granted January 31, 1939.

In the drawings:

25 Fig. 1 is a side elevational view of a roller bit in accordance with the invention;

Fig. 2 is a vertical section through the bit, taken substantially in the plane of the axis of the cross cutting rollers;

30 Fig. 3 is a vertical section similar to Fig. 2, but illustrating another embodiment of the invention;

Fig. 4 is a vertical section similar to Fig. 2, but illustrating still another embodiment of the invention;

35 Fig. 5 is a detail horizontal view, taken in the plane V—V of Fig. 4; and

Fig. 6 is a vertical sectional view showing the construction of one of the side cutting rollers.

Referring first to Figs. 1 and 2, the roller bit therein disclosed comprises a body member 1 having a threaded stub 2 on the upper end thereof for attachment to a drill shaft and having four downwardly depending arms 3, 4, 5 and 6 thereon for supporting cutting rollers, arms 3 and 4 being juxtaposed to each other in spaced apart relation, and arms 5 and 6 being likewise in juxtaposed spaced apart relation relative to each other and displaced 90° about the body 1 from the arms 3 and 4, respectively. The arms

45 3 and 4 support a main cutting roller assembly, constituting the present invention, and the arms 5 and 6 support auxiliary outer, inclined, side cutting rollers in accordance with the usual practice, one of these auxiliary cutting rollers 40

50 being shown in Fig. 1.

Referring now to Fig. 2, arms 3 and 4, respectively, have inwardly extending stub shafts 7 and 8, respectively, thereon which may be welded to the arms 3 and 4, respectively, and each stub shaft has an aperture extending therethrough, 5 the aperture 9 in the stub shaft 7 being in alignment with the aperture 10 in the stub shaft 8 and both of these apertures being centrally disposed with respect to the outer surfaces of the stub shafts. A main pin or cross shaft 11 extends through and is fitted in the apertures 9 and 10 and supports a bushing 12 positioned between the inner ends of the stub shafts 7 and 8, respectively. Positioned in alignment between the arms 3 and 4 are four cutting rollers 13, 14, 15 and 16, respectively. The cutting roller 13 is rotatably supported by rollers 17 and balls 18 on a bearing member 19, which is threaded to screw onto the stub shaft 7, the outer surface of the latter being threaded to receive the member 20 19. The cutting rollers 14 and 15 are rotatably mounted on bearing rollers 20 and 21, respectively, directly on the bushing 12. Cutting rollers 14 and 15 are separated longitudinally by a flange 22 on bushing 12, this flange 22 having its outer 25 periphery cut in polygonal shape, or having teeth cut in its periphery, to permit engagement by a tool for turning the same during assembly and disassembly, as will be described later.

The cutting roller 16 is rotatably supported 30 by bearing rollers 23 and balls 24 on a bearing member 25, which is threaded to screw onto the stub shaft 8.

When the structure described is assembled, the pin 11 is solidly locked in the apertures 9 35 and 10 against any movement with respect to the arms 3 and 4, the bushing 22 is solidly locked against movement with respect to the pin 11, and the bearing bushings 19 and 25 are firmly locked against movement on the stub shafts 7 40 and 8, respectively.

I secure these results in a demountable structure as follows:

The pin 11 is rigidly fixed in the aperture 10 45 in stub shaft 8 by tapering the latter aperture from a large diameter at the outer end to a smaller diameter at the inner end thereof and correspondingly tapering the end portion of pin 11 so that when the shaft is drawn to the left 50 (as shown in Fig. 2) it wedges firmly in the aperture 10 in stub shaft 8. I further prevent any possible rotation of pin 11 after it has been placed in position by providing a pin 27 in the end thereof, the end of the pin projecting from the 55

pin 11 into a recess 28 provided therefor in the arm 4.

To firmly lock the left end of the pin 11 in the aperture 9 in the stub shaft 7, the latter aperture is flared slightly to a larger diameter at its outer end and the left end of the pin 11 is counterbored and threaded to receive a tapered screw plug 29. The counterbored portion of the pin 11 is also provided with radial slots 30 which divide the end of the shaft into segments which are expanded outwardly tightly against the walls of the aperture 9 when the screw plug 29 is screwed into the counterbore.

To lock the bushing 12 against movement with respect to the pin 11, the latter is provided with threads 32 which engage with cooperating threads on the inner surface of the bushing 12 at the right end thereof. By applying a suitable wrench to the flange 22 on bushing 12, the bushing can be screwed tightly onto the threaded portion 32 of pin 11, clamping the right end of bushing 12 firmly against the inner end of the bearing member 25 on the stub shaft 8 on arm 4, and thereby preventing any possible movement, in operation, of the bushing 12.

The inner ends of the bearing members 19 and 25 are provided with radial slots 34 and 35, respectively, adapted to receive a suitable wrench for turning the bearing members during assembly and disassembly.

The roller elements described with reference to Fig. 2 are assembled as follows: First the bearing member 10, carrying the bearing rollers 17, the bearing balls 18 and the cutting roller 13, is screwed onto the stub shaft 7, and the assembly comprising the cutting rollers 16, bearing rollers 23, bearing balls 24 and bearing member 25 are placed in position by screwing the bearing member 25 onto the shaft 8. These operations are performed while the pin 11, bushing 12 and the cutting roller elements supported thereon are removed. Then the assembly of the bushing 12, bearing rollers 20, cutting roller 14 and the bearing rollers 21 and cutting roller 15 is slid into position between the juxtaposed ends of the cutting rollers 13 and 16. Then the pin 11 is inserted through the aperture 10 and the bushing 12 until the threads 32 thereon abut against the ends of the threads in bushing 12, after which the bushing 12 is rotated, by means of a suitable wrench applied to the flange 22, to screw the threaded portion of bushing 12 onto the threads 32 of pin 11, this screwing action drawing the pin 11 from right to left until it is seated solidly in the aperture 10 and the bushing 12 is drawn up tight against the bearing member 25. The pin 11 is then firmly locked in the aperture 9 by inserting the screw plug 29 and screwing it up tight. While turning force is being applied to the plug 29 the outer face of the arm 3 may be struck with a hammer to move the arm in until the inner end of the bearing member 19 presses tightly against the end of the bushing 12, the arm 3 being secured in such inner position because of the left end of the pin 11 being expanded outwardly against the tapered end portion of the aperture 9 by the plug 29. The structure shown in Fig. 2 may be disassembled by merely reversing the operation described; that is, first removing the plug 29, then rotating the bushing 12 to disengage the threaded portion thereof from the threads 32 on the pin 11, this action automatically moving the pin to the right out of tight engagement with the stub shaft 8, completely removing the pin 11, then removing

the bushing 12, and the elements supported thereon, and finally removing the bearing bushings 19 and 25 and the cutting rollers assembled thereon.

The modification shown in Fig. 3 differs from Fig. 2 in that all of the cutting rollers are mounted on a unitary bushing which may be inserted or removed as a unit from the bit, and in the use of a slightly different expanding bolt or plug on the end of the main cross shaft. Thus the structure of Fig. 3 comprises a body member 1' having downwardly depending juxtaposed arms 3' and 4' for supporting the cross cutter roller assembly. Arms 3' and 4' are provided with aligned apertures 50 and 51, respectively, each of which is flared from a small diameter to a larger diameter at the outer surface of the associated arm. These apertures 50 and 51 receive and support a main pin 52 which is provided with an outwardly flaring head 53 at one end and adapted to seat in the flared aperture 51 and is provided at the other end with segments 54 adapted to be forced outwardly into locking engagement with the flared aperture 50 by the head of a bolt 55 screwed into a threaded recess in the end of pin 52.

The pin 52 supports a bushing composed of two sections 56 and 57, respectively, which bushings are adapted to be interengaged to each other by means of an externally threaded extension 58 on section 57 which screws into a threaded recess provided in the end of bushing section 56. Bushing section 57 is internally threaded adjacent its outer end to receive external threads 59 on the pin 52. To prevent rotation of the bushing sections with respect to the arms 3' and 4' a lock screw 60 is threaded into each of the arms, each screw being adapted to fit in one of a plurality of recesses 61 positioned in the outer ends of the bushing sections 56 and 57, respectively, and symmetrically spaced about the axes of the bushings.

In the particular construction shown in Fig. 3, four cutting rollers 63, 64, 65 and 66 are mounted on the bushing between the arms 3' and 4'. Cutting roller 63 is supported on the bushing section 56 by roller bearings 70 and ball bearings 71. The cutting rollers 64 and 65 are mounted on the bushing section 56 by roller bearings 72 and 73, respectively, and the cutting roller 66 is mounted on the bushing section 57 by a roller bearing 74 and a ball bearing 75.

The structure described with reference to Fig. 3 is very strong and rigid in operation because the pin 52 is held solidly within the arms 3' and 4' and by virtue of the extensible end segments 54 on the left end of the shaft and the flared head 53 on the other end, the two arms 3' and 4' are drawn tightly against the ends of the bushing, preventing any longitudinal motion thereof. The bushing is further retained against any longitudinal motion by the threads 59 on the pin 52. Any rotation of the bushing is not only resisted by the friction between the ends of the bushing and the arms 3' and 4' and the threads 59 on the pin 52, but is further positively prevented by the set screws 60 which engage in the apertures 61 in the opposite ends of the bushing.

However, when desired, the cutting roller can be very easily and quickly removed and replaced by a new assembly consisting of a new bushing having all four new cutters preassembled thereon. Thus to disassemble the structure shown in Fig. 3, the lock bolt 55 is first removed from the end of the pin 52 and then the shaft withdrawn by inserting 75

a screw-driver in the slotted head thereon and rotating the screw to the left, causing the threads 59 on the shaft to screw out of the bushing section 57, thereby forcing the shaft to the right and contracting the segments 84 in the left end thereof, so that they can pass through the aperture 80. By the time the threaded portion 59 of the shaft is disengaged from the threads in the bushing section 57 the head 53 of the shaft can be grasped with any suitable tool and completely withdrawn. The lock screws 60 are next partially or completely withdrawn, whereupon the entire assembly, including the bushing sections 56 and 57 and the cutting rollers rotatably mounted thereon, can be dropped out from between the arms 3' and 4'. Assembly of a new roller assembly is performed in reverse manner. Thus the assembly is inserted between the arms 3' and 4' of the shaft 52 partly inserted to support the cutter assembly. The bushing is then rotated to bring apertures 81 in alignment with the lock screws 60 and the latter set up. The pin 52 is then screwed home and locked in place by inserting the lock screw 55 in the end thereof.

25 Each bushing bearing roller and cutter roller assembly may be disassembled after removal from the drill by unscrewing the two bushing sections 56 and 57, after which the roller cutter 66 may be pulled off of the bushing section 57 and the roller cutters 63, 64 and 65 may be pulled off the bushing section 56.

The modification shown in Fig. 4 differs from those shown in Figs. 2 and 3, in that the tubular bushing has been eliminated and a different method of locking the main cross shaft is employed. Thus referring to Fig. 4, the bit therein depicted comprises a body member 1" having downwardly depending juxtaposed arms 3" and 4", which arms are provided near their lower ends 40 with a pair of juxtaposed apertures 80 and 81, respectively, for receiving a main cross pin 82. Both of the apertures 80 and 81 are tapered or flared so that their outer orifices are of larger diameter than their inner orifices and one end of 45 the pin 82 is correspondingly tapered to fit snugly within the aperture 81. The opposite end of pin 82 is divided into segments 84 adapted to be expanded radially outwardly into snug engagement with the tapered aperture 80.

50 To expand the segments 84, the pin 82 is made hollow to receive a rivet 85 which extends therethrough from one end to the other. The rivet 85 has a tapered head 86 on one end which is driven into the shaft and bears against and expands the 55 segments 84 to fit tightly in the aperture 80. The rivet 85 is retained in set position by upsetting its opposite end 87 so that it expands to fill a flared seat 88 in the right end of the pin 82.

A pair of cutting rollers 90, both of which are 60 identical and identically mounted, are supported on the pin 82. Thus each cutting roller 90 is radially supported for free rotation on the pin 82 by two sets of roller bearings 91 and 92. Outward axial thrust of each cutting roller 90 is taken 65 by a row of ball bearings 93 positioned between a race 94 formed in the cutting roller and a race 95 formed in a block 96, which is supported in part by the adjacent arm 3" or 4", and in part by the pin 82. Thus each block 96 has a cylindrical aperture therein for snugly engaging the pin 82 so that it is supported against any radial movement by the shaft. Each block 96 is supported against rotary movement by the adjacent arm 3" or 4".

70 Thus referring to Fig. 5, the block 96 is pro-

vided with a pair of tenons 97 which fit in a groove 98 in the inner face of the associated arm.

The structure of Fig. 4 is assembled and disassembled as follows:

Each of the cutting rollers 90, its associated roller bearings 91 and 92, ball bearings 93 and block 96 is moved into position adjacent one of the arms 3" or 4" by sliding the tenon 97 on the block 96 upwardly in the groove 98. The assembly, including the other cutting roller 90, 10 roller bearings 92 and 93 and block 96, is similarly inserted. Then the cross pin 82 is inserted first through aperture 81, then through the two roller assemblies, and into the aperture 80, being driven into position with the enlarged right end fitting snugly into the flared aperture 81. The rivet 85 is then inserted in the pin 82 from left to right and drawn up tightly by hammering it on the head 86 to spread the segments 84 tightly against the wall of the aperture 80 and hammering it on the opposite end to upset the latter and form the head 87 to retain the rivet in position.

The bit may be disassembled by first driving out the rivet 85 from right to left, the upset right end being drawn out in the process, and then removing the pin 82, after which the cutting roller assemblies may be slid out of the body.

The structure for supporting the side cutting rollers 40 is illustrated in Fig. 6. Thus there is attached to the arm 5, as by welding, a downwardly and inwardly extending stub shaft 100 having a threaded end portion 101 and a threaded shoulder 102, which is of larger diameter and positioned back of the threaded end portion 101. 30

The shoulder 102 receives an internally threaded bearing member 103, which is screwed tightly thereon, this bearing member forming an inner race for radial roller bearings 104, and half of the inner race for ball thrust bearings 105. To 40 complete the inner race for the ball bearings 105 a second internally threaded bearing member 106 is screwed onto the outer threaded portion 101 of the shaft 100. This member 106 forms one-half of the inner race to receive balls 105 and is locked in position after assembly. To this end, the internal diameter of the threaded opening in member 106 is larger at the outer end than at the inner end, and the end portion of the shaft 100 is slotted to form segments 107 which can be expanded outwardly into tight engagement with threaded member 106. These segments 107 are expanded after assembly in the same manner as the segments 84 on the cross shaft are expanded; namely, by means of a tapered rivet. This rivet 111 extends through a central passage in the shaft 100 and is provided with a head 112 on its inner end which expands the segments 107 when the rivet is drawn up tight as by driving the heads 112 and upsetting the outer end 113 to retain the rivet in position.

The radial roller bearing 104 and the thrust ball bearing 105 rotatably support the side cutting roller 40 directly, as shown in Fig. 6, the roller being provided with suitable races to bear 65 against the rollers 104 and balls 105.

Although the invention has been explained by describing in detail a specific embodiment thereof, it is to be understood that various changes can be made from the specific structure shown, 70 without departing from the invention, and the latter is to be limited only to the extent set forth in the appended claims.

I claim:

1. A roller bit comprising a frame member 75

having a pair of spaced-apart supporting members, a shaft supported by and extending between said supporting members, a sleeve non-rotatably supported on said shaft between said supporting members, and cutting roller means rotatably supported on said sleeve.

2. A roller bit comprising a frame member having a pair of spaced-apart supporting members having aligned apertures therein, a shaft extending through said apertures and supported by said supporting members at its opposite ends, means for releasably anchoring the ends of said shaft rigidly to said supporting members, a bearing member on said shaft between said supporting members, means for releasably anchoring said bearing member rigidly to said shaft, and cutting roller means rotatably supported on said bearing means.

3. A roller bit comprising a frame member having a pair of spaced-apart downwardly depending arms in juxtaposed relation, said arms having aligned apertures therein, a pin extending through said apertures and supported by said arms at its opposite ends, a bushing means mounted on said pin between said arms, means for limiting inward movement of one end of said pin with respect to the adjacent arm, and means for releasably expanding the opposite end of said pin, the aperture in the arm receiving said opposite end of said pin being of larger diameter at its outer end than at its inner end and cutting roller means rotatably supported on said bushing means.

4. A roller bit comprising a frame member having a pair of spaced-apart downwardly depending arms in juxtaposed relation, said arms having aligned apertures therein, a pin extending through said apertures and supported by said arms at its opposite ends, said pin having a threaded portion intermediate said arms, a bushing mounted on said pin between said arms and having internal screw threads engaging the threads on said pin, and cutting roller means rotatably mounted on said bushing.

5. A roller bit comprising a frame member having a pair of spaced-apart downwardly depending arms in juxtaposed relation, said arms having aligned apertures therein, a pin extending through said apertures and supported by said arms at its opposite ends, said pin having a threaded portion intermediate said arms, a bushing mounted on said pin between said arms and having internal screw threads for engaging the threads on said pin, means for limiting inward movement of one end of said pin with respect to the adjacent arm, means for releasably expanding the opposite end of said pin, the aperture in the arm receiving said opposite end of said pin being of larger diameter at its outer end than at its inner end.

6. A roller bit as described in claim 4, in which said bushing has wrench-engaging means thereon, accessible from the exterior of the assembled bit, whereby said bushing can be turned after assembly of the cutting roller means thereon to tighten or loosen the threaded connection between the pin and bushing.

7. A roller bit as described in claim 4, in which said bushing has wrench-engaging means thereon, accessible from the exterior, whereby it can be turned after assembly of the cutting roller means thereon to tighten or loosen the threaded connection between the pin and bushing, and cooperating means on said pin and one at least

of said arms for preventing rotation of the pin with respect to the arms.

8. A roller bit as described in claim 4, in which said aperture in one of said arms is larger at its outer end than at its inner end and the corresponding end of said pin is tapered to wedge into said aperture in response to relative rotation between said threaded bushing and said pin with the end of the bushing bearing against the inner face of said arm.

9. A roller bit as described in claim 3, in which said opposite end of said pin is split into segments, counterbored and threaded, and a threaded plug screwed into said counterbore for expanding the end of the pin into tight engagement with the aperture in said arm.

10. A roller bit as described in claim 3 in which said bushing means fills the space between said arms and is gripped between said arms in response to expansion of said opposite end of said pin.

11. A roller bit as described in claim 3, in which said opposite end of said pin is provided with a large counterbore and a smaller threaded counterbore extending into the pin from the bottom of the large counterbore, the portion of the pin surrounding the large counterbore being split into segments, and a bolt adapted to be screwed into said threaded counterbore and having a head for bearing against and expanding said segments outwardly in the aperture in the associated arm.

12. A roller bit comprising a frame member having a pair of spaced-apart arms with inwardly extending stub shafts on said arms, said stub shafts having concentrically aligned apertures therein, a shaft extending through said apertures and supported by said stub shafts at its opposite ends, bearing members on said stub shafts, cutting roller means rotatably supported on said bearing members, a stationary bearing member on said shaft between said stub shafts, cutting roller means rotatably supported on said last mentioned bearing members, and means for releasably anchoring said first mentioned bearing members on said stub shafts and said last mentioned bearing member on said shaft.

13. A roller bit comprising a frame member having a pair of spaced-apart downwardly depending arms in juxtaposed relation, said arms having aligned apertures therein and having inwardly extending stub shafts concentrically positioned with respect to said apertures, a pin extending through said apertures and supported by said arms at its opposite ends, a bushing mounted on said pin between the inner ends of said stub shafts, cutting roller means rotatably mounted on said bushing, cutting rollers on said stub shafts, and bearing means for rotatably mounting said cutting rollers on said stub shafts.

14. A roller bit as described in claim 13, in which said bearing means for rotatably mounting said cutting rollers on said stub shafts comprise stationary bearing members fitted on said two stub shafts, and means including said bushing interposed between the inner ends of said stationary bearing members for locking them against inward movement along said stub shafts.

15. A roller bit as described in claim 4, with means for locking said bushing against rotation with respect to one at least of said arms.

16. A roller bit comprising a frame member having a pair of spaced-apart supporting members having aligned apertures therein, a shaft extending through said apertures and supported

by said supporting members at its opposite ends, means for releasably anchoring said shaft to said supporting members, a sleeve member on said shaft comprising two sections screwed together,

5 releasable locking means for independently locking each of said members against rotation with respect to said spaced-apart supporting members, and cutting roller means rotatably supported on said sleeve means.

10 17. A roller bit as described in claim 16, in which said sleeve member comprises end portions of larger diameter than the midportion, and bearing means cooperating with said enlarged portions of said sleeve means to retain said cutting rollers against longitudinal escape from said sleeve when the sleeve bearing and cutting assembly is detached from the drill, the two sections of said sleeve member being interconnected between said enlarged portions thereof, whereby

15 20 said cutting rollers may be disassembled from said sleeves following disassembly thereof.

18. In a roller bit, a hollow shaft, a member encircling one end of said shaft, said end having slots therein dividing it into segments and means 25 expanding said segments into locking relation with said member, comprising a rod member extending through said hollow shaft and having a tapered head within said segments, and means on the opposite end of said rod member engaging

20 25 the adjacent end of said shaft for maintaining the tapered end of said rod member in expanding relation with said segments.

19. In a roller bit, a hollow shaft, a member encircling one end of said shaft, said end having 30 slots therein dividing it into segments and means expanding said segments into locking relation with said member, comprising a rivet extending through said hollow shaft from end to end and having a tapered head within said segments, the opposite end of said rivet being upset whereby it

engages the adjacent end of the shaft for maintaining the tapered end of said rivet in expanding relation with said segments.

20. A roller bit comprising a frame member having a pair of spaced-apart supporting members, a hollow shaft supported by and extending between said supporting members, cutting roller means rotatably supported on said shaft between said supporting members, said shaft extending into and being supported in tapered apertures in 10 said supporting members, one end of said shaft having a tapered head thereon for engaging in one of said tapered apertures and the other end being segmented, and a rod member extending through said hollow shaft and having a tapered 15 head within said segments for expanding the same against the walls of the aperture in the associated supporting member, and means on the opposite end of said rod member engaging the adjacent end of said shaft for maintaining the 20 tapered end of said rod member in expanded relation with said segments.

21. A roller bit comprising a frame member having a pair of spaced-apart supporting members, a shaft supported by and extending between 25 said supporting members, cutting roller means on said shaft, radial bearing means rotatably supporting said cutting roller means on said shaft, a thrust bearing means comprising a stationary member 30 encircling the said shaft and radially supported thereby, and cooperating means on one of said supporting members and said stationary member for preventing rotation of said stationary member, said cooperating means comprising cooperating guide means on said supporting member and on said stationary member, respectively, said guide means guiding said stationary member for linear motion only in a predetermined path radial with respect to said shaft. 35

JOHN T. PHIPPS.
